UNITED STATES PATENT OFFICE

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

FOLDING MACHINE AND METHOD

Application filed June 24, 1921, Serial No. 480,177. Renewed May 31, 1928.

The present invention relates to folding methods and machines, and more particularly to methods of and machines for folding a binding strip around the edge of a boot or shoe upper to which it is attached. The more important features of novelty of the present invention are claimed in Letters Patent No. 1,527,396, granted February 24, 1925. The claims of the present application are restricted to subsidiary features of novelty, many of which are of broader application than to folding machines.

In finishing the edges of boot and shoe uppers, it is usual either to fold the previously skived margin of the upper over upon itself, or else to fold over upon the margin a binding strip that has previously been sewed to the upper. This folding operation may be performed in a folding machine, through which the upper is progressively advanced or fed to the folding instrumentalities. In the interest of economy, such folding machines should be operated at high speed. It is easy enough to operate a properly designed folding machine at high speed when folding along straight portions of the stock. Difficulties occur, however, at the curved portions, particularly those portions that are very sharply curved. At such portions, the stock must be fed through the machine either at a lower speed or by shorter feed strokes.

An object of the present invention, therefore, is to provide in a folding machine having a feed mechanism, an improved, automatically acting mechanism for varying the feed strokes. The range of the feed strokes may be varied automatically from zero to a maximum. The zero, or substantially zero, range is particularly valuable at sharp, convex curves, for the stock is not then fed forward at all,—or is fed but very little,—but is simply turned in its plane by the operator while the other operating instrumentalities perform the folding.

Another object of the invention is to provide an improved method of folding shoe uppers and similar articles.

If the binding strip is to lie smoothly at the curved margins of the upper, particularly the concave margins, it must be snipped at

those portions, as is well known. It is among the objects of the present invention to provide an improved machine for effecting this snipping, and a feature of the invention contemplates employing a separator that separates the binding strip from the upper as a stationary member of the snipping mechanism.

A further object of the invention is to provide, in a folding machine, a snipping knife that is automatically disconnected from its actuating shaft at the end of a predetermined, limited, rotative movement of the latter.

With the above and other objects in view, as will become clear in the course of the following description, the invention consists of the improved method and machine an embodiment of which is hereinafter described, illustrated in the accompanying drawings, and defined in the appended claims.

In the drawings:

Figure 1 is an elevation, partly in longitudinal section, upon a reduced scale, of a machine embodying the present invention, the treadle mechanism being shown detached and upon a further reduced scale;

Figure 2 is a section similar to Figure 3, showing the parts occupying relatively different positions;

Figure 3 is a section taken substantially upon the line 3—3 of Figure 1, looking in the direction of the arrows;

Figure 4 is a view of a treadle, showing treadle rods loosely connected thereto;

Figure 5 is a section taken substantially upon the line 5—5 of Figure 2, looking in the direction of the arrows;

Figure 6 is a section taken upon the line 6—6 of Figure 2, looking in the direction of the arrows;

Figure 7 is a perspective view of a preferred combined separator and stationary knife, shown in conjunction with the movable knife;

Figure 8 is an enlarged view of a portion of the same;

Figure 9 is a perspective view of the upper forward part of the machine, parts being broken away for clearness;

15 Figures 15, 16 and 17 are sections taken substantially upon the lines 15—15, 16—16 and 17—17, respectively, of Figure 14, looking in the direction of the arrows; and

Figure 18 is a perspective view illustrating 20 the folding action at a sharp convex curve.

The invention is illustrated in the accompanying drawings in connection with the folding of a binding strip 2, of cloth, silk 25 and the like, around the edge 4 of a sheet of leather or other material 6, such as a boot or shoe upper. An edge 8 of the binding strip is stitched at 12 to a face 10 of the shoe upper along the edge 4, so that the sheet and the strip extend at an angle to 30 each other from the secured-together edges 4 and 8. It will be understood that the invention is equally applicable to other articles than that which is herein chosen for purposes 35 of illustration, and the elements of the article need not necessarily be of the relative dimensions shown.

The shoe upper is initially placed in the machine upon a platform or support 24, Figure 9, with the face 10 of the upper in contact 40 with the support. An end of the free or unsecured edge 26 of the strip 2 is initially moved across and around the secured-together edges 4 and 8, and into the space 45 between a feed point 30 and a plow 32 that stands up integrally from a plate 34. The machine being set into operation, successive portions of the unsecured edge or portion of the strip 2 near the stitches 12 are intermittently wiped tightly across the secured-together edges 4 and 8, or away from the 50 stitches, as shown more particularly at 36, Figure 13, by the combined action of a wiper 38 and a retainer 246 that presses down heavily at this time upon the upper directly opposite to the point of action of the wiper. It 55 is very important to the subsequent operation that the strip be wiped very tightly. In order to enable the wiper 38 to operate, the strip 2 is progressively moved lightly or 60 loosely by the operator's fingers from the position of Fig. 12 more or less into the plane of the shoe-upper sheet 6, as the shoe upper is fed forward through the machine. The successively wiped portions are initially folded 65

around the secured-together edges 4 and 8 by the plow, during its backward movement with the feed elements, as described in the said Letters Patent No. 1,527,396. The plow is of gradual-incline construction in the line of feed, as illustrated more particularly in Fig. 10, to effect a gradual folding of the strip around the edge of the sheet. The plow-folded portions of the strip are intermittently gripped between the feed point and the plow 70 32, becoming thereby pulled tightly. The intermittent wiping, and folding and gripping operations are performed upon the successive portions of the strip alternately during successive pauses in the feed. The plow-folded 75 portions are advanced by the feed point and a cooperating feed block 41, that is carried integrally with the plow 32 upon the plate 34, to a combined folder and fold presser 42. The fold presser 42 folds the plow-folded 80 portions of the strip further and presses them down against the other face 16 of the sheet, as shown in Fig. 18. The preferred fold presser 42 is described in the said Letters Patent and in Letters Patent No. 1,527,395, 85 also granted February 24, 1925. These operations are continued in timed relation to one another until the whole strip has become folded, as described more fully in the said Letters Patent No. 1,527,396. Reference is 90 made to the said Letters Patent for a fuller description of so much of the machine as is not fully disclosed herein, because unnecessary to an understanding of the present invention.

The preferred wiper 38 is also fully described in the said Letters Patent No. 1,527,396, and need not, therefore, be further described here. A modified wiper, having a somewhat greater range of diagonal movement out of the plane of the stock, is disclosed in a copending application, Serial No. 633,120, filed April 19, 1923.

The binding strip is maintained in folded position upon the face 16 of the leather by 110 previously applied, wet cement. A machine adapted for use with dry-cemented strips is disclosed in a copending application, Serial No. 605,374, filed December 7, 1922. If the initially folded wet cemented strip were permitted to contact with the edges 4 and 8 before it has become tightly gripped and pulled tight by the combined action of the feed point and the plow, it would not be possible to pull the strip tight, and the resulting fold would be defective. A separator 143 is therefore provided, near the diagonally cut-away, front portion of the plow, to maintain the strip 115 separated from the raw edges 4 and 8 until after the feed point and the plow have had an opportunity to pull the strip tight. By reason of the diagonally cut-away, or inclined construction, a more gradual folding effect is obtained than would be possible if the plow 120 were not so inclined. The separator 143 may, 125

if desired, extend forward across the plow to a point very close to the fold presser, but the construction shown more particularly in Figures 7, 8 and 10 is found to be sufficient, in practice. The separator is carried upon the end of an arm 145 that is pivoted about a stud 147 mounted on the upper end of the bracket 61. The separator is floating, being maintained yieldingly in the illustrated, active position by a spring 149, but it may be pivotally lifted out of the way, when desired, by pressing down upon a finger piece 151 integral with the arm 145 upon the other side of the pivotal stud 147. The separator 143 is constituted of resilient or yielding material, so that it may float in the space between the edges 4 and 8 and the partly turned binding strip. This is of great advantage when turning sharp convex corners, as the separator floats with the stock while the material is turned in its plane at sharp curves. If the separator could not yield at such places, it would pull the stock away from the fold presser, resulting in poor folding. As the separator yields, however, the fold presser is enabled to maintain its grip upon the work. In the specific construction shown, the separator comprises a spring lying loosely in a groove 263 of the arm 145 and extending through an opening 255. One end (not shown) of the spring separator 143 is hooked or otherwise secured to the under side of the arm 145.

The separator is maintained in place between the binding strip and the raw edges 4 and 8 until the forward movement of the feed elements, carrying the stock with them, causes the separator to be left behind. The binding strip cannot, therefore, stick to the edges 4 and 8 before it has been properly folded over.

Sometimes, it is desired to have the stock rest upon a table 176, shown in Figure 1 as supported by adjustable abutments 178, and encircling the platform or support 24 and the operating mechanisms. Upon other occasions, this table may be pivotally moved out of the way about a pivotal axis 171.

The retainer 246 presses down upon the stock and operates as described in the said Letters Patent No. 1,527,396.

The retainer-operating mechanism is fully illustrated and described in a copending application Serial No. 407,336, filed September 1, 1920.

An arm 250 of somewhat greater length than that of the retainer is provided for the purpose of contacting with a stationary part of the machine at 252, so that when the machine runs idly, the retainer 246 cannot become lowered into contact with the wiper and, by hammering away at the wiper, injure it. The point 252 is in the present instance shown on the upper face of a bracket 61. The bracket 61 is vertically adjustable, as described in the said Letters Patent No. 1,527,396, through

the medium of screws 63 in enlarged openings 65 of the bracket. Compensating adjustment for the arm 250 is therefore necessary. It is, furthermore, frequently desired to adjust the arm 250 relative to the retainer 246 to accommodate stock of different thickness. A very simple adjustment is illustrated in Figure 11. The retainer arm 250 is bent at 253, and is provided on either side of the bend with countersunk openings 255', adapted to receive the heads of screws 257. The screws 257 may be threaded into screw-threaded openings 259 upon the retainer arm 153. To adjust the arm 250, the screws 257 are loosened, the arm 250 is adjusted to the desired position upon the retainer 153, and the screws 257 are then tightened.

Before the machine is started, it is desirable to raise the feed point from the feed block to permit the insertion of the upper therebetween. A preferred construction for raising the feed point is illustrated and described in the said Letters Patent No. 1,527,396, and comprises an intermediately pivoted lever 307 that is normally maintained in the illustrated position (Fig. 1) by a spring 310 coiled about a rod 312. A treadle 313, acting upon a link 316, is adapted to actuate the lever 307 so as to cause the raising of the feed point 30, as illustrated and described in the said Letters Patent No. 1,527,396. The feed point, in turn, raises the retainer by engaging the under side of the arm 250.

In order that the binding strip may lie smoothly upon the face 16 of the leather sheet after folding, it is desirable to snip the strip at concave portions of the work, as shown at 174, Figure 10. Such snipping is performed in the present machine, after the wiper and the plow have acted, and just prior to the folding operation, while the strip is partly turned against the separator, as will be understood from Figure 7. A sharp-pointed knife 352 is caused to pierce or puncture the strip at an intermediate or interior point, while the stock is clamped down, and the knife is then swung outward, between the legs 353 of the separator support, towards the free edge 26 of the strip, to snip the margin of the strip from the interior point outward to the edge. The knife is mounted upon the end of a knife-carrying bar 354 that is pivoted at 356 to one end of a link 358 the other end of which is pivoted about the stud 147 between prongs 360 at the upper end of the bracket 61. Adjustment of the bracket 61 has no appreciable effect upon the operation of the knife. The other end of the knife-carrying bar 354 is provided with a circular opening 362 eccentrically disposed to an opening 364 in a gear 366, thus constituting an eccentric strap. The gear 366 meshes with the gear 154 upon the driving shaft, and so is continuously driven therefrom. The knife bar 354 is adapted to be clutched to the gear 366 by a

novel clutching mechanism that will now be described.

For convenience of manufacture, the gear 366 is formed of two parts, one the gear proper, which is annular in shape, as will be understood from Figures 2, 3 and 5, and the other a body portion 368 to which the annular gear is secured by screws or bolts 370. The body portion 368 is integrally provided with a hollow shaft 372 mounted in a bearing 374 of the machine frame, and the hollow shaft is held in place within the bearing by a screw 376 threaded into a screw-threaded opening 378 of the hollow shaft and the head of which engages a washer 380. The hollow shaft is continuously rotated within the bearing 374 because thus rigidly secured to the annular gear. A second hollow shaft 382 is rotatably mounted within the hollow of the shaft 372, and is held against longitudinal movement therein by a pin 384 extending through openings 386 at opposite sides of the hollow shaft 372 and between annular shoulders 388 of an annular groove 390 formed upon the hollow shaft 382. A shaft 392 is longitudinally slidably mounted within the hollow of the shaft 382, but is prevented from rotating therein by a pin 394 fixed to the shaft 392 and extending into a longitudinally disposed opening 396 of the hollow shaft 382. A coil compression spring 398 within the hollow of the shaft 382 acts upon the inner end of the shaft 392 to press it normally outward. The shaft 392 is adapted to be pressed inward against the force of the spring by a lever 400. The gear 366 is provided with a plurality of openings 402. As the gear 366 continuously rotates, one of these openings will become rotated into line with the pin 394, which will be forced by the lever 400 into the said opening 402. The pin will thereupon act as a clutching element against a side wall of the said opening 402 to clutch the shaft 392 and, through it, the hollow shaft 382, to the gear 366 so as to be rotated thereby. An eccentric 404 that is integral with the free end of the hollow shaft 382 and that is mounted within the eccentric opening 362 thereupon actuates the knife-carrying bar 354. The eccentric is for convenience shown mounted also within an opening 406 of a plate 408 that is secured adjacent to the eccentric opening 362 of the knife-carrying bar by screws or the like 410, an annular flange 412 of the eccentric being held in place by a countersink 414 upon the plate 408, and a disk 416, secured to the eccentric by screws 418, engaging the outer face of the plate 408. At the end of one complete revolution, or any other desired predetermined movement of the gear 366, an opening 420, Figure 6, of the knife-carrying bar 354 will register with the said opening 402 of the gear, whereupon, assuming that the lever 400 has become moved out of the way, the spring 398 will force the shaft 392 into its

normal position, and the clutching pin 394 out of the opening 402 and into the opening 420, where it normally rests. The knife-carrying bar will thus become disconnected from its driving gear 366. So long as the lever 400 is maintained in the position of Figure 3, however, the knife bar will be continuously actuated.

The lever 400 is under the control of the operator, so that the knife-carrying bar may be rendered effective or ineffective, at will. The lever 400 is shown intermediately pivoted about the same pivotal point 171 about which the table 176 is pivoted, and its other end is hooked at 422 to one end of treadle rod 424 the other end of which is loosely connected to the other end of the treadle 313. The treadle 313 is adapted normally to occupy an intermediate position, as shown in Figure 4, in which it is ineffective. Upon the operator moving the treadle in one direction, the treadle rod 316 will act upon the lever 307 to actuate the feed point, as above described. Actuation of the treadle 313 in the other direction, beyond the intermediate, ineffective position, will pivot the lever 400 about its pivotal point from the position of Figure 2, in which the knife is ineffective, to the position of Figure 3, in which the knife is active. The knife is normally ineffective, and can be rendered effective, owing to the construction of the treadle 313 and the treadle rods 316 and 424, only when the feed point is down.

As illustrated and described in the said Letters Patent No. 1,527,396, friction clutch faces 70 and 72, Fig. 1, may be caused to engage more or less firmly by suitable manipulation of a treadle 81, acting through a link 82 and a bell-crank lever 78, thus providing for varying the speed of rotation of the driving shaft 66. According to the present invention, slowing down the speed of the machine in this manner automatically reduces the rate of feeding movement, so that curved parts of the material are fed through the machine not only at less speed, but by shorter feed strokes as well. This desired result is brought about, in the illustrative machine, by automatically adjusting the eccentricity of the eccentric 106 upon the end of the shaft 66, in accordance with the value of the speed of rotation of the shaft 66, causing the rocking support (shown in Letters Patent No. 1,527,396 at 94) that carries the feed elements 30 and 41 to be rocked, through greater or less amplitudes of rocking movement, as the case may be. The said rocking support may, indeed, be maintained absolutely stationary, preventing any feed movement at all, which is very desirable when very sharp concave or convex portions of the stock are encountered. At such places the wiper, the fold presser and the other operating instrumentalities continue to operate while no feeding at all takes place, the operator simply turning the stock in its plane to

permit successive portions of the margin to become successively folded. The operation will be understood more particularly from Figure 18, where the edge 26 of the binding strip is shown crowded a little by minute stages at 448. The crowding is of so minute a character, that for practical purposes, the edge fold is perfectly smooth, unmarred by any wrinkles or bunching whatsoever. The action of the diagonal pinching edge 144 of the fold presser 42 materially contributes to the desired result; for as the edge 144 extends rearward a substantial distance across the sharp convex edge of the material, the fold is thereby pinched, not straight across, but at an angle to the strip. Feed control of this character is believed to be produced herein for the first time, and is considered to be of far greater application than to binding-strip-folding machines in particular, or shoe machines in general. The specific construction employed will now be described.

The driving shaft 66 is shown more particularly in Figure 14, provided with a longitudinal eccentric bearing 450 for a second shaft 452 upon the forward end 454 of which the eccentric or crank stem 106 is carried. The bearing 450 may be produced by longitudinally drilling through the shaft 66, or preferably, the shaft 66 may be made hollow to start with and bushings 456 plugged into its ends. The bushings are eccentrically bored to provide the bearing 450. The space 458, between the bushings, may be utilized as an oil chamber. According to the actual construction illustrated, but one bushing 456 is employed, at the rear end of the shaft, the forward end being shown solid. The forward wall of the oil chamber 458 is indicated, in dotted lines, at 460. In whatever manner the structure is manufactured, it will be clear that, by rotatably adjusting the shaft 452 within the bearing 450, the eccentric or crank stem 106 may be made to assume different eccentric positions upon the forward end of the shaft 66. According as the crank stem is adjusted nearer to or farther from the center of the shaft, the feed steps will be shortened or lengthened. If the crank stem is caused to assume a position exactly central of the shaft, as illustrated in Figure 14, it will remain exactly central throughout the rotation of the shaft, and the shaft will continue to rotate without rocking the said rocking support; and the feed elements will therefore remain at rest.

The length of the feed strokes is automatically varied in accordance with the variation in speed by connecting the shaft 452, through the medium of segmental gears 462 and 464, to governor weights 466. The weights 466 and the segmental gears 462 and 464 are integral with arms 468 that are pivoted at 470 to the hand-and-balance wheel 68. As the machine speeds up, the governor weights are

centrifugally forced outward pivotally about the pivotal points 470, causing the gears 464 and 462 to rotate the shaft 452 within its bearings 450. As the machine slows down, very stiff springs 472, each attached at one end 474 to the arms 468 and at the other end 476 to a stationary part of the balance wheel 68, draw the governor weights back toward normal position, correspondingly rotatably adjusting the shaft 452. Any intermediate rate of feed between maximum and minimum values may be obtained by speeding the machine up more or less, as desired, the variable centrifugal force acting upon the governor weights 466 at different speeds being always balanced by the variable tension on the springs 472 corresponding to those speeds.

To increase or decrease the normal tension on the springs, the ends 476 are secured, not directly to the hand-and-balance wheel, but to diametrically opposed points of a spring collar 478 that is split at 480 to facilitate its mounting within an annular groove 482 of the hand-and-balance wheel 68. The collar 478 is provided with gear teeth 484 that mesh with the teeth of a pinion 486 that is secured, as by means of a pin 488, to a plunger 490. The plunger 490 is mounted within a recess 492 in the web 494 of the hand-and-balance wheel 68 and is maintained in the outward position illustrated in Figure 16 by a coil compression spring 496. The pinion 486 is provided with ratchet teeth 498 that engage ratchet teeth 500 upon the inner face of a block 502 that is set in position within a recess 504 upon the periphery of the hand-and-balance wheel. The plunger 490 extends through an opening 506 of the block 502 and its head is slotted at 508 to receive a screw driver. When it is desired to adjust the normal tension of the springs 472, a screw driver is inserted in the slot 508, the plunger 490 is forced inward by pressing in on the screw driver, in opposition to the force of the spring 496, thereby disengaging the ratchet teeth 498 from the ratchet teeth 500. The screw driver is then turned to rotate the pinion 486, in one direction, or the springs 472 are permitted to effect rotation of the pinion in the opposite direction. Rotation of the pinion causes rotation of the split collar 478 in one or the other direction. Releasing the screw driver results in the plunger becoming spring-forced back into place, to cause the ratchet teeth 498 and 500 to engage once more, locking the split collar in adjusted position.

The limits of the rate of feed may be adjusted by slidably adjustable stops 510 and 512, the former adapted to be engaged by one of the governor weights 466 to limit the outward movement of the governor, and the latter by the other governor weight 466 to limit its inward movement. By adjusting the stop 510, the maximum rate of feed may

be adjusted; by adjusting the stop 512, the minimum rate of feed may be controlled within any desired limits between zero and any other desired minimum value. The stops 510 and 512 may be adjusted by rotating screw-threaded rods 514 that are threaded through screw-threaded openings 516 of the stops. The screw-threaded rods 514 are mounted in bearings 518 and 520. Collars 521 prevent longitudinal movement of the rods 514.

As will be understood from Figures 1 and 14, the gear 462 is held against the bushing 456 by a button 522 that is screwed into the forward end of a short shaft 524 mounted in the bearing collar 526. For purposes of convenience in assembly, the bushing 456 and the shaft 524 are provided with annular flanges 528 and 530, respectively, that are secured to each other and to the hand-and-balance wheel 68 by screws 532.

Although the invention has been described above in connection with a special machine disclosed in the above-identified Letters Patent No. 1,527,396, it will be understood that this is for illustrative purposes only, and that the invention is of broader scope, unlimited except in so far as limitations may be specifically imposed in the appended claims.

What is claimed as new is:

1. A machine for folding a strip around the edge of a sheet of material to one face of which, along the said edge, an edge of the strip is secured so that the sheet and the strip extend from the secured-together edges at an angle to each other, the said machine having, in combination, means for moving the unsecured edge of the strip across the secured-together edges, means for folding the strip around the secured-together edges, a separator adapted to lie between the strip and the secured-together edges, and a movable knife for slitting the unsecured edge of the folded strip, the separator constituting a stationary knife for cooperating with the movable knife to effect the slitting of the folded strip.

2. The method of snipping the margin of a strip of material that comprises clamping the strip at a point removed from the said margin, puncturing the unclamped margin at an interior point with a sharp-pointed instrument, and swinging the instrument outward towards the edge of the strip to snip the margin from the interior point outward to the edge.

3. A machine of the class described having, in combination, means for clamping a strip of material at a point removed from the margin thereof, a sharp-pointed knife, and means for actuating the knife to puncture the unclamped margin at an interior point, the actuating means acting thereafter to swing the knife outward towards the edge

of the strip to snip the margin from the interior point to the edge.

4. A machine of the class described having, in combination, feeding means, a shaft for actuating the same having a gear, a gear meshing with the shaft gear, a knife, and a clutch for connecting the knife so as to be driven by the second-named gear.

5. A folding machine having, in combination, folding means, a knife, a shaft for actuating the folding means and the knife, and means for automatically disconnecting the knife from the shaft upon a predetermined degree of rotation of the shaft.

6. A machine of the class described having, in combination, a pivotally mounted platform upon which material is adapted to rest, a knife and a lever for controlling the knife pivotally mounted about the pivotal point of the platform.

7. A machine of the class described having, in combination, a frame, a retainer, an element against which the retainer is adapted to clamp material, means for actuating the retainer towards and from the element to clamp and unclamp the material, the retainer having an arm adapted to engage the frame to prevent the retainer being actuated into contact with the element when no material is interposed between the retainer and the element, and means whereby the arm may be adjusted.

8. The method of folding a strip around the edge of a sheet of material to one face of which, along the said edge, an edge of the strip is secured so that the sheet and the strip extend from the secured-together edges at an angle to each other, the said method comprising feeding the sheet and the strip, folding the strip around the secured-together edges with a plow of gradual incline construction in the direction of the line of feed to cause a gradual folding of the strip around the said edge of the sheet, and pressing the folded strip into contact with the other face of the sheet.

9. A machine of the class described having, in combination, feeding means comprising a normally effective feed point, normally ineffective cutting means, a treadle connected to the feed point and the cutting means, and means whereby the treadle is adapted selectively to render the feed point ineffective and the cutting means effective.

10. A folding machine having, in combination, a support, a wiper mounted on the support, a retainer cooperating with the wiper having an arm adapted to rest upon the support, means whereby the support may be adjusted, and means whereby the arm may be adjusted.

11. A machine of the class described having, in combination, a support, a feed point, a retainer having an arm adapted to rest upon the support, means for moving the feed point,

and means whereby movement of the feed point effects movement of the arm from off the support.

12. A machine for folding the margins of sheet material having sharp convex edges having, in combination, a feed block and a feed point for feeding the material, a plow for folding the margin of the material, and a fold presser for pressing the folded margin, the fold presser having a diagonal edge extending rearward a substantial distance across the sharp convex edges, and the feed point having a face correspondingly cut away diagonally, the feed point being adapted to be moved forward towards the fold presser so that its diagonal face shall be very close to the diagonal edge of the fold presser.

13. A machine for folding a strip around the edge of a sheet of material to one face of which, along the said edge, an edge of the strip is secured so that the sheet and the strip extend from the secured-together edges at an angle to each other, the said machine having, in combination, a wiper for wiping the strip tightly across the secured-together edges, a plow for initially folding the strip around the secured-together edges after it has been wiped, the plow having a diagonally cut-away portion, a separator adapted to lie between the strip and the secured-together edges near the cut-away portion, and a fold presser for pressing the initially folded strip into even contact with the other face of the sheet.

14. A machine of the class described having, in combination, a frame, means for feeding material step by step, a retainer, an element against which the retainer is adapted to clamp material, and means for actuating the retainer towards and from the element to clamp the material during pauses in the feed and to unclamp the material, the retainer having an arm adapted to engage the frame to prevent the retainer from being actuated into contact with the element when no material is interposed between the retainer and the element.

15. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip, a plow for folding the strip around the secured-together edges, the plow being of gradual incline construction in the direction of the line of feed to effect a gradual folding of the strip around the said edge of the sheet, and a fold presser for pressing the folded strip into contact with the other face of the sheet.

16. The method of folding the margin of a sheet of material the edge of which is variously curved, said method comprising turn-

ing the material in its plane and holding it against feeding movement while folding the curved portions of the margin, and feeding the material while folding other portions of the margin.

17. A folding machine having, in combination, a fold presser, means for feeding sheet material the edge of which is sharply curved to the fold presser and means operable during the operation of the machine for controlling the feeding means to hold the material against feeding movement while permitting turning of the material in its plane during the action of the fold presser upon sharply curved portions of the margin, the fold presser and the feeding means being situated close to each other to permit the fold presser to act upon the sharply curved portions of the margin, while the material is turned in its plane without being fed.

18. A folding machine having, in combination, means for folding sheet material, means for feeding material to the folding means by step-by-step feed strokes, means for controlling the speed of the feeding means, and means for varying the lengths of the feed strokes in accordance with the speed of operation of the feeding means.

19. A folding machine having, in combination, means for folding sheet material, means for feeding the material to the folding means, and means controlled in accordance with the speed of operation of the feeding means for varying the rate of feed of the feeding means.

20. A method of folding sheet material that comprises feeding the material by step-by-step feed strokes, folding the material at a predetermined point in the path of feed, varying the speed of the feed of the material, and varying the lengths of the feed strokes in accordance with the speed of the feed.

21. A method of folding sheet material that comprises feeding the material, folding the material at a predetermined point in the path of feed, varying the speed of the feed of the material, and varying the rate of the feed of the material in accordance with the speed of the feed.

In testimony whereof, I have hereunto subscribed my name this 9th day of June, 1921.

ANDREW R. RIDDERSTROM.
